UNITED STATES PATENT OFFICE.

WILLIAM K. SPAULDING, OF KETCHIKAN, TERRITORY OF ALASKA.

DESIGN FOR A BADGE, BUTTON, PENDANT, OR SIMILAR ARTICLE.

52,410.

Specification for Design.

Patented Sept. 10, 1918.

Application filed May 10, 1918. Serial No. 233,810. Term of patent 7 years.

To all whom it may concern:

Be it known that I, WILLIAM K. SPAULDING, a citizen of the United States, residing at Ketchikan, First Judicial Division, Territory of Alaska, have invented a new, original, and ornamental Design for a Badge, Button, Pendant, or Similar Article, of which the following is a specification, reference being had to the accompanying drawing, forming a part thereof.

The figure is an elevation of a badge, button, pendant or similar article, showing my new design.

I claim:

The ornamental design for a badge, button, pendant or similar articles, as shown.

WILLIAM K. SPAULDING.
